UNITED STATES PATENT OFFICE.

ELIZABETH M. GOODWIN, OF LOS ANGELES, CALIFORNIA, ASSIGNOR TO PROCESS DEVELOPMENT COMPANY, OF LONG BEACH, CALIFORNIA, A CORPORATION OF CALIFORNIA.

DESIGN FOR A HOT-WATER BOTTLE OR SIMILAR ARTICLE.

Application filed March 5, 1929. Serial No. 30,332. Term of patent 14 years.

To all whom it may concern:

Be it known that I, ELIZABETH M. GOODWIN, a citizen of the United States, residing at Los Angeles, in the county of Los Angeles and State of California, have invented a new, original, and ornamental Design for a Hot-Water Bottle or Similar Article, of which the following is a specification, reference being had to the accompanying drawings, forming part thereof.

Fig. 1 is a plan view of a hot water bottle, or similar article, showing my new design.

Fig. 2 is a bottom view of Fig. 1.

Fig. 3 is a side view.

I claim:

The ornamental design for a hot water bottle, or similar article, as shown.

ELIZABETH M. GOODWIN.
